 Tony Hom(57) **CLAIM**

The ornamental design for a smart camera, as shown and described.

DESCRIPTION

FIG. 1 is a perspective view of a smart camera showing my new design;

FIG. 2 is another perspective view thereof;

FIG. 3 is a front elevation view thereof;

FIG. 4 is a back elevation view thereof;

FIG. 5 is a right side view thereof;

FIG. 6 is a top plan view thereof; and,

FIG. 7 is a bottom plan view thereof.

The left side view is omitted as it is a mirror image of the right side view. The broken lines in the drawings depict portions of the smart camera and form no part of the claimed design.
